[57] CLAIM

The ornamental design for an eyebrow shaper razor, as shown and described.

DESCRIPTION

FIG. 1 is a left side elevational view of an eyebrow shaper razor showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is left side elevational view thereof.
The broken line showing of a blade cover in FIG. 2 is for illustrative purposes only and forms no part of the claimed design.
